Max Weil

Application July 9, 1952, Serial No. 20,531

Term of patent 3½ years

(Cl. D44—15)

To all whom it may concern:

Be it known that I, George A. Baker, a citizen of the United States of America, residing at Walnut Park, California, in the county of Los Angeles and the State of California, have invented a new, original, and ornamental Design for a Plate, or Similar Article, of which the following is a specification, reference being had to the accompanying drawing, forming part thereof.

The figure is a plan view of a plate of a conventional configuration, showing my new design. The dominant features of my design reside in the portions shown in full lines.

I claim:

The ornamental design for a plate, or similar article, as shown and described.

GEORGE A. BAKER.
